CLAIM

The ornamental design for a frame for a traffic barricade, as shown and described.

DESCRIPTION

FIG. 1 is a reduced perspective view of a frame for a traffic barricade showing our new design with the broken lines shown for illustrative purposes only and forming no part of the claimed design;

FIG. 2 is a left side elevational view thereof, with the opposite side being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a front elevational view of a second embodiment thereof;

FIG. 8 is a left side elevational view thereof, with the opposite side being a mirror image;

FIG. 9 is a top plan view thereof;

FIG. 10 is a bottom plan view thereof;

FIG. 11 is a rear elevational view thereof;

FIG. 12 is a sectional view taken along line 12—12 of FIG. 7; and,

FIG. 13 is a partial sectional view taken along line 13—13 of FIG. 7.

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 13.

FIG. 12.
